DESIGN FOR A FLASHLIGHT

Bernard Francis Muldoon, Mountain View, N. J., assignor to Henry Hyman, Brooklyn, N. Y.

Application December 6, 1940, Serial No. 97,109

Term of patent 14 years

To all whom it may concern:

Be it known that Bernard Francis Muldoon, a citizen of the United States and resident of Mountain View, in the county of Passaic and State of New Jersey, has invented a new, original, and ornamental Design for a Flashlight, of which the following is a specification, reference being had to the accompanying drawing forming part thereof, in which,

Fig. 1 is a front elevational view of a flashlight with its swivel head pointing upwardly, showing my new design;

Fig. 2 is a top plan view thereof;
Fig. 3 is a side elevational view thereof; and
Fig. 4 is a rear elevational view thereof with the swiveled head pointing sidewise.

The dominant features of the design reside in the portions shown in full lines.

I claim:

The ornamental design for a flashlight, substantially as shown and described.

BERNARD FRANCIS MULDOON.
